BIT FOR ROCK DRILLING

Silas A. Knowles, Denver, Colo.

Application May 21, 1948, Serial No. 28,482

2 Claims. (Cl. 255—64)

1

This invention relates to improvements in bits of the type employed in connection with rock drilling.

Wherever mining or tunneling is carried on, as well as in many other places, it becomes necessary to drill rocks for use in connection with blasting and for many other purposes.

The simplest form of rock drill is made from a steel bar sharpened to a chisel point, or provided with crossed cutting edges, which are sharpened and flattened so as to facilitate the cutting and penetration of the rock.

Since the discovery of extra hard metals such as tungsten carbide, drill bits have been constructed in such a way that the cutting tips or edges are made from this metal.

It is the object of this invention to produce a rock drill having a removable bit which can be made from extra hard steel or from tungsten carbide or any other metal that may be found suitable, and it shall be so constructed that it can be readily removed and replaced whenever necessary.

A further object of the invention is to produce a drill bit of such construction that the drill steel can be formed to the desired shape with the least possible expense and with the greatest degree of accuracy.

The above and any other objects of the invention that may appear as the description proceeds are attained by means of a construction and an arrangement of parts that will now be described in detail and for this purpose, reference will be had to the accompanying drawing in which the invention has been illustrated, and in which:

Figure 1 is a side elevation showing a section of drill steel provided with a removable-bit constructed in accordance with this invention;

Figure 2 is a side elevation taken at right angles to that shown in Figure 1;

Figure 3 is a view showing a portion of the drill steel and the bit in cross section and a portion of the steel in elevation;

Figure 4 is a cross section taken on line 4—4, Figures 1, 2 and 3;

Figure 5 is a top plan view looking through plane 5—5, Figure 2;

Figure 6 is a top plan view looking through plane 6—6, Figure 7;

Figure 7 is a side elevation, partially in section, similar to that shown in Figure 3;

Figure 8 is a side elevation looking through plane 8—8, Figure 9; and

Figure 9 is an end view of the drill shown in Figure 8.

2

Referring now to the drawing, reference numeral 15 designates a drill steel or bar which may be of circular cross section or of any other shape. Such drill steel is usually provided with axial openings 16 through which water and air may be introduced into the drill hole. Openings 16 are usually formed during the rolling or drawing of the steel, but may be drill holes if desired. The type of the drill steel is formed into wedge shape by a suitable milling cutter which leaves two outwardly tapering surfaces 17 and which also forms a diametrical cut 18 extending the whole width of the drill steel.

The drill bit which forms part of this invention may be made from very hard tool steel or from tungsten carbide or from any other material that may be found to be suitable. Such drill bits must, of course, be very hard and have sufficient strength to prevent them from accidentally breaking during operation.

The drill bit which is shown in the drawing consists of a bar 19 of a width and depth to fit the diametrical cut 18. The outer edge of bar 19 is wedge-shaped and tapers to a point 20, which is usually slightly rounded and forms the cutting edge. Extending from the ends of the bar are two arcuate portions 21 whose inner surfaces are curved in such a way as to fit the outer surface of the drill steel as shown in Figure 6. The connecting members 21 are flattened along the sides as indicated at 22. This provides passages 23 between the drill and the wall of the drill hole, (Figures 5, 6 and 9), for the escape of water, air and rock during the operation.

In Figures 5 and 6 the outline of the drill hole has been indicated by broken lines. When tungsten carbide is employed, the drill bit is usually constructed in the manner shown in Figure 6, but if the drill bit is made from steel, the sides 21, instead of extending from one end of the bar to the other, may be formed from shorter portions like those designated by reference numeral 21a in Figures 2, 4 and 5. When the construction shown in Figures 4 and 5, for example, is employed, a greater space or opening is provided for the escape of crushed stone, water and air than when the construction shown in Figure 6 is used. The construction shown in Figures 4 and 5 may, of course, be employed in connection with tungsten carbide, if desired.

The drill bit is made in such a way that it fits the drill steel quite snugly and after it has been positioned on the drill steel, it is connected with it by some suitable solder or it may be brazed to the drill steel or connected thereto in any other suit-

able manner. It is, of course, desirable and necessary that the drill bit shall be fastened to the drill steel as securely as possible and this is usually accomplished by sweating or soldering. The solder is selected in such a way that it will melt at a temperature that will not damage the drill steel and the drill bit may, therefore, be removed and replaced without requiring the drill steel to be heated to a temperature that will damage it. The curved sides 21 and 21a have their front edges inclined so as to lie in planes parallel to the planes of inclined surfaces 17 and are preferably positioned slightly below the outer edge of the inclined surfaces, as shown in Figures 2 and 3. The center or cutting bar 19 projects slightly beyond the edge of the sides 17 so as to permit it to wear to some extent before getting into coplanar alignment with the wedge surfaces.

As has already been pointed out, the axial opening 16 in the drill steel is employed for introducing water or water and air, or air alone into the drill hole so as to remove the rock dust formed by the drilling. In the construction shown in Figure 3, the outer end of hole 16 has been bored to a slightly larger diameter, as indicated at 24. This leaves segment-shaped openings 25 on opposite sides of cutting bar 19 through which the water or air may enter. The dust, as well as the water or air, returns through passages 23 which are clearly shown in Figures 5, 6 and 9. With the construction shown in Figures 2 and 3, the center portion of cutting bar 19 is left unsupported, which is sometimes objectionable, and wherever such construction is not desired, the width of opening 16 is made of the diameter of opening 16 so that the cutting bar will fit snugly against the sides of the opening, the whole diameter of the steel. When so constructed the brazing or soldering is continuous over the whole length of the cutting bar. With the construction shown in Figure 7, the air or water exits through openings 26.

A chisel cutting edge like that shown in Figures 1 to 7, inclusive, is believed to be preferable to the cross cutting edges shown in Figures 8 and 9, but, if for any reason a construction like that shown in Figures 8 and 9 is desired, the drill bits may readily be made so as to provide such a construction.

With the construction shown in Figure 9, there are two diametrical cuts 18a and two cross bars 19a connected by portions 21b. It will be noted that the parts 21b are substantially straight, leaving escape passages 23, of which four are shown.

Attention is called to the fact that with the above construction the drill bit is formed from a single piece and can be very quickly positioned on

the drill steel. When a chisel type drill bit is employed, the end of the drill steel can be quickly and readily made into the proper shape by a milling cutter, thus assuring that all of the drill steels will be identical and reducing the cost of manufacture. Where several cutting edges are used and separate pieces of tungsten carbide introduced into each, the work and expense of preparing the drill is greater than with the construction shown here. The cutting bar is readily accessible to sharpening, if this should become necessary. When a construction like that shown in Figures 8 and 9 is used, it is very difficult to sharpen the cutting bars.

15 What is claimed as new is:

1. A rock drill comprising, a tubular drill steel having its point inclined from opposite sides to form a wedge, the wedge-shaped end having a diametrical cut in the plane bisecting the angle of the wedge, and a hard bit having a bar positioned in the cut, projecting beyond the line of intersection of the planes of the wedge sides, the ends of the bit bar having arcuate extensions embracing the drill steel, the end edges of said extensions lying in planes substantially coincident with the corresponding wedge surfaces of the bar.

2. A rock drill comprising a tubular drill steel having one end wedge-shape, and provided with a diametrical cut parallel with the bisector plane of the wedge angle, and a bit of hard material comprising a bar of a thickness equal to the width of the cut, and a length equal to the diameter of the bar, positioned in the cut, the outer edge being transversely wedge-shape, the ends of the bar terminating in arcuate portions embracing the outer surface of the drill steel, the outer edges of the drill steel embracing portions being substantially parallel with the planes of the wedge surfaces.
